UNITED STATES PATENT OFFICE.

EMILE KRIPPENDORF, OF WOOD HAVEN, ASSIGNOR TO THE LALANCE & GROSJEAN MANUFACTURING COMPANY, OF NEW YORK, N. Y.

TEA OR COFFEE POT.

SPECIFICATION forming part of Letters Patent No. 276,976, dated May 1, 1883.

Application filed February 12, 1883. (No model.)

To all whom it may concern:

Be it known that I, EMILE KRIPPENDORF, a citizen of the United States, residing at Wood Haven, in the county of Queens and State of New York, have invented certain new and useful Improvements in Tea or Coffee Pots, of which the following is a specification.

My invention relates to that class of tea or coffee pots or similar vessels which are composed of sheet metal and provided with a lip or spout of like material for directing the outflow of the contents; and it consists in an improved method of uniting the spout to the body of the vessel, the object of the invention being to produce a joint impervious to the inclosed liquid, thereby preventing the liability to leakage common to joints as heretofore made and applied in this class of utensils.

In tea and coffee pots of this character as heretofore constructed the lip has in most cases been secured by first forming an outwardly-projecting flange upon the portion of the edge of the lip which it is intended shall be attached to the body of the vessel, said flange being lapped and by rivets or soldering directly secured thereto, the portion of the body of the vessel inclosed within said flanged edges of the lip having previously been perforated with a suitable number of small holes, forming a strainer to prevent the outflow of sediment or other solid matters of any kind.

Experience has shown that riveted joints, as above described, are liable to give way and become leaky in consequence of the expansion and contraction caused by the changes of temperature to which articles of this kind are necessarily exposed, permitting the access of moisture, which is followed by rapid oxidization of the parts, thus destroying the usefulness of the vessel.

My invention dispenses entirely with the use of rivets in uniting the lip to the body of the vessel, and forms a double seamed or lapped joint which is absolutely water-tight and is not affected by variations of temperature.

In the accompanying drawings, Figure 1 is a view in elevation of a side of the lip and a portion of the body of the vessel, showing the former before its attachment to the latter. Fig. 2 is a front elevation of the body of the vessel before the attachment of the lip. Fig. 3 is an inside elevation of the lip; and Figs.

4 and 5 are sectional plan views, showing the lip in different stages of attachment.

In these figures, A represents the main body of the vessel, which is formed in the usual manner of iron or other sheet metal. B is a strainer formed from the side of the body A, being severed therefrom at three of its sides, as shown, but left uncut at its upper portion. The strainer is shown as sprung slightly outward from the body A, which may preferably be caused by contracting the edges of the body adjacent to those of the strainer.

The usual lip, C, for directing the outflow of the contents of the vessel, is provided with a groove or indentation, c, extending throughout the edges D E F, and from which projects a flange, f. The flanged edges D E F should correspond in shape with the strainer B.

The lip C is attached to the body A by first inserting the free end of the strainer B within the interior of the groove c of the lip C, and by forcing the latter upward the flange f may be made to fit tightly between the edges of the strainer B and the adjacent edges of the body A. The parts will then assume the positions shown in Fig. 4. The inwardly-projecting flange f is next bent down closely over the inner edge of the body A, as shown in Fig. 5, forming a double lapped or seamed joint, which is then compressed, by means of a die or otherwise, so as to be perfectly water-tight in every part. The completed vessel may be finished by tinning, enameling, or otherwise, as desired. The joint thus formed, owing to its elasticity, may be subjected to expansion and contraction without injury, while its broad bearing-surfaces and re-entering angles and the absence of rivets render it absolutely water-tight under all the ordinary conditions of use, thus avoiding the liability to leakage or corrosion.

I claim as my invention—

1. The combination, substantially as hereinbefore set forth, of the body of a tea or coffee pot or other like vessel, a strainer forming an integral part of the side of said vessel, but partially separated therefrom, and a lip having the corrugated edges D E F intervening between the adjacent edges of said strainer and vessel, whereby said vessel, strainer, and lip may be firmly clamped together.

2. The combination, with the body of a tea

or coffee pot or other like vessel, of a strainer forming an integral part of the side of said vessel, but partially separated therefrom, and adapted to be clamped within the joint of attachment of the lip or spout with said body of the vessel, substantially as hereinbefore set forth.

In testimony whereof I have hereunto subscribed my name this 8th day of February, A. D. 1883.

EMILE KIPPENDORF.
